ICE BLOCK FORMING AND DISPENSING DEVICE

Richard A. Bayne, Detroit, Mich.

Application June 29, 1939, Serial No. 281,928

11 Claims. (Cl. 62—108.5)

This invention relates to an ice block forming and dispensing device.

In my previous application Serial No. 185,271, filed January 17, 1938, I have shown a device positionable within the sharp freezing chamber of a refrigerator provided with a plurality of spaced divider plates which form spaces in which the water is frozen to form ice blocks. This device automatically dispenses the ice blocks one by one while still in the refrigerator but preparatory to refilling the device with water for forming additional ice blocks the divider plates must be manually returned to their respective ice block forming positions.

This invention contemplates an improvement upon the above-mentioned device in that the ice blocks are not only automatically dispensed one by one but the divider plates are also automatically returned to their original or ice block forming positions.

It is also an object of this invention to produce such an ice block forming and dispensing device which is of simple structure, cheap to manufacture, and easily and efficiently operated.

In the drawings:

Fig. 1 is a plan view partly in section showing the device with one ice block channel loaded ready for dispensing and the other with the plates in their respective positions after all the ice blocks have been discharged.

Fig. 2 is a section along the line 2—2 of Fig. 1.

Fig. 3 is a front elevation of the device showing the operating handle in its three operating positions.

Fig. 4 is a section along the line 4—4 of Fig. 2.

Fig. 5 is a vertical section showing the first ice block being discharged.

Fig. 6 is a fragmentary plan view showing the divider plates being automatically returned to their respective ice block forming positions.

Fig. 7 is a fragmentary perspective showing the detail mounting of the divider plates on the ejector tube.

Fig. 8 is a detail showing the arrangement for selectively positioning each of the divider plates in its proper ice block forming position.

Referring more particularly to the drawings there is shown a sheet metal tray generally designated 1 provided with channels 2 and 3 in which the ice blocks are formed, side walls 4 and 5 and end wall 6. The forward ends of the channels 2 and 3 are open. A support plate 7 is positioned forwardly of the open end of the

channels 2 and 3 by and fixed to the plates 8 which are fixed to the forward ends of the side walls 4 and 5 of the tray.

To form ice blocks each of the channels 2 and 3 are divided into ice block forming spaces by the divider plates 9, 10, 11, 12, 13, 14, 15 and 16. The divider plates, as shown particularly in Figs. 7 and 8, are mounted upon a square tube 17 which passes through openings 18 provided therefor in each of the divider plates. The divider plates are provided with spring clutch fingers 19 which project outwardly and forwardly from the forward face of the plates and yieldably engage the opposite side walls of the tube 17. For the purposes of this description the ice block dispensing or outlet end of the tray is considered the forward end of the tray.

It will be noted that due to the inclination of these clutch fingers 19 with respect to the tube 17 that the tube 17 will move freely forwardly or to the left, as viewed in Figs. 1 and 7, of the divider plates but upon reverse movement the fingers 19 will tend to clutch the tube 17 with greater force and friction than when the tube is moved forwardly. Thus whenever the tube 17 is moved rearwardly the divider plates will be carried with it unless sufficient resistance is offered which will cause the tube 17 to slide with respect to the fingers 19 in spite of their slip clutch action. This resistance is provided in the form of a plurality of stops 29, 30, 31, 32, 33, 34, 35 and 36.

It will be seen that there is provided a pair of stops for each of the divider plates. The distance between each pair of stops decreases from the forward to the rear end of the tray, that is, stops 29 are slightly farther apart than stops 30, stops 30 farther apart than stops 31. In other words, each pair of stops is closer together than the pair of stops immediately forward thereof. The stops 29 through 36 conveniently take the form of side plates 31 and middle plate 38 which are cut to shape and fixed to the top of the tray above and lengthwise of the channels 2 and 3. Each of the divider plates is arranged so that the width of its upper end is greater than the distance between its respective pair of stops and less than the distance between the stops forwardly thereof. Thus the distance between the vertical edges 40 of the plate 15 is greater than the distance between its respective stops 35 and less than the distance between the stops 34. Thus the width of the upper portion of each plate, that is, the dis-

tance between its vertical edges, is less than the width of the plate forwardly thereof.

Although the divider plates slide relative to the tube 17 they cannot turn thereon due to the fact that opening 18 is square like the cross section of the tube 17. Further, any torque that is transmitted to the divider plates is taken up by the lugs 41 which slidably engage the guides 42.

An ejector 45 is fixed to the end of the tube 17 and a closure plate 46 with a rubber sealing gasket 47 for the front or open end of the channels 2 and 3 is slidably mounted on the tube 17 and normally retained in closed position by the stop lugs 48 which back up and position the closure plate 46.

The tube 17 is slidably mounted on the fixed rod 43 one end of which is fixed as at 44 in the rear end wall 6 of the tray and the forward end of which is supported on the plate 7. The forward end of the fixed rod 43 is reduced as at 49 and has slidably mounted thereon the thrust screw 50. The thrust screw 50 is brazed or otherwise suitably fixed to the tube 17 as at 51. A nut 52 is screwed upon the screw 50. A handle 53 is swivelled to the nut 52. The nut 52 is provided with opposed fingers 54 which form a rotary bolt.

A keeper 55 adapted for interengagement with the rotary bolt 54 is secured to the support 7. As shown in the full lines, right hand side of Fig. 3, the handle 53 is in vertical position and the bolt 54 is interengaged with the keeper 55. If the handle 53 is turned counter-clockwise ninety degrees to the dotted line position, the rotary bolt is turned from the horizontal to the vertical and disengaged from the keeper 55. This permits the tube 17 to be pulled outwardly or to the left, Fig. 1.

The operation of the device is as follows: In the lower half of Fig. 1 the device is shown in ice block forming position with the divider plates 10 spaced, the closure 46 closed and the handle 53 in vertical position with the rotary bolt 54 horizontal and interengaged with keeper 55. After the ice is formed and while the tray 1 is still in the sharp freezing compartment of the refrigerator, the handle 53 is turned counterclockwise, Fig. 3, approximately forty-five degrees. Since the square tube 17 cannot be turned and the screw 50 is fixed to the tube 17, therefore the screw 50 cannot turn. Since the nut 52 and bolt 54 are still interengaged with the keeper 55 and cannot move outwardly or toward the left, Fig. 1, thus as the nut 52 turns forty-five degrees on the screw 50, the screw 50 and the tube 17 move forwardly or toward the left a short distance, about one-sixteenth of an inch. The turning of nut 52 on screw 50, due to the mechanical advantage thereof, exerts a considerable forward and leftward pull, Fig. 1, on the tube 17 which detaches the ejector plate 45 from the end wall 6 to which it might be frozen, breaks loose the ice blocks from the side and bottom walls of their respective channels 2 and 3, and slightly opens the closure 46. The handle 53 is now turned another forty-five degrees to the horizontal position shown in dotted lines Fig. 3, which disengages the rotary bolt 54 from its keeper. The handle 53 may now be pulled forward or to the left carrying with it the entire column of ice blocks until the closure 46 will abut the inner face of the guide 60 for the square tube 17.

The distance between the rubber gasket 47 on the closure 46 from the outer edge 61 of channel

3 (when the closure 46 abuts the guide 60, Fig. 5) is less than the length of two ice blocks 62 plus the thickness of one divider plate between them. Thus only one ice block 62 will be entirely forwardly of and free from the discharge end 61 of the channel 3. The second ice block 62a is retained by the forward edge 61 of the channel.

The ice blocks are disconnected from the divider plates by the inclined surface 63 as explained in my copending application Serial No. 276,530, filed May 31, 1939. The first ice block 62 will be released as soon as the operator ceases to pull on the handle 53. If the handle is again pulled forwardly or to the left, divider plate 9 is drawn against the closure plate 46 and the second ice block 62a is discharged upon easing the pull on the handle 53. This method of operation is repeated until all of the ice blocks are discharged and the divider plates will be stacked in the position shown in the upper half of Fig. 1. The forward or ejecting movement of handle 53 is arrested, when the last ice block is discharged, by the ejector plate 45 abutting the stops 65 at the forward or outlet end of the channels.

To reload the tray the handle 53 is pushed rearwardly or to the right, Fig. 1. The clutching engagement between the fingers 19 and the square tube 17 causes the plates to move rearwardly or to the right. As the tube 17 moves to the right the stops 29 through 36 inclusive select or arrest their corresponding divider plates 9 through 16 and position them in their properly spaced relation. As soon as the ejector plate 45 abuts the end wall 6 the handle 53 is turned from the vertical position, Fig. 3, full line to the horizontal position, dotted line showing Fig. 3. During the last forty-five degrees of clockwise turning of the handle 53 the threaded engagement of nut 52 and screw 50 causes the plate 46 and gasket 47 to be drawn tightly against the outlet end of the channel 3. Obviously since the ice forming and dispensing mechanism is identical for both of the channels 2 and 3, the operation of these mechanisms is identical and the description of the one applies equally well to the other.

In reloading as the tube 17 is moved rearwardly or to the right, stops 48 abut closure 46 and force it into closing relation with the discharge end of the tray.

I claim:

1. A device for forming and dispensing ice blocks comprising a container having an outlet and adapted to receive a liquid to be frozen, a plurality of divider plates cooperating with the walls of the container to form ice cube compartments, ejecting means slidably forwardly and backwardly, said ejecting means on its forward movement being adapted to loosen the ice blocks and move the ice blocks and said divider plates through said outlet to dispense the ice blocks, and mechanism cooperating with said slidably ejecting means on its backward movement for returning the divider plates to and spacing the divider plates in their original ice block forming positions within the container.

2. A device for forming and dispensing ice blocks comprising a container having an outlet and adapted to receive a liquid to be frozen, a plurality of divider plates cooperating with the walls of the container to form ice cube compartments, ejecting means slidably forwardly and backwardly, said ejecting means on its forward movement being adapted to loosen the ice blocks and move the ice blocks and said divider

plates through said outlet to dispense the ice blocks, means for juxtapositioning said plates after they have been ejected through said outlet, and mechanism cooperating with said slideable ejecting means on its backward movement for returning the divider plates to and spacing the divider plates in their original ice block forming positions within the container.

3. A device for forming and dispensing ice blocks comprising a container having an outlet and adapted to receive a liquid to be frozen, a plurality of divider plates cooperating with the walls of the container to form ice cube compartments, ejecting means movable forwardly and backwardly, said ejecting means on its forward movement being adapted to loosen the ice blocks and move the ice blocks and said divider plates through said outlet to dispense the ice blocks, a breakable driving connection between each of said plates and the said ejecting means, and stop means for selectively engaging said divider plates on the backward movement of said ejecting means to break the driving connection between the ejecting means and the divider plates and space the divider plates in their original ice block forming positions within the container.

4. A device for forming and dispensing ice blocks comprising a container having an outlet and adapted to receive a liquid to be frozen, a plurality of divider plates cooperating with the walls of the container to form ice cube compartments, ejecting means movable forwardly and backwardly, said ejecting means on its forward movement being adapted to loosen the ice blocks and move the ice blocks and said divider plates through said outlet to dispense the ice blocks, means for juxtapositioning said plates after they have been ejected through said outlet, a breakable driving connection between each of said plates and the said ejecting means, and stop means for selectively engaging said divider plates on the backward movement of said ejecting means to break the driving connection between the ejecting means and the divider plates and space the divider plates in their original ice block forming positions within the container.

5. A device for forming and dispensing ice blocks comprising a container having an outlet and adapted to receive a liquid to be frozen, a plurality of divider plates cooperating with the walls of the container to form ice cube compartments, ejecting means movable forwardly and backwardly, said ejecting means on its forward movement being adapted to loosen the ice blocks and move the ice blocks and said divider plates through said outlet to dispense the ice blocks, a breakable driving connection between each of the said divider plates and the ejecting means, a plurality of stops spaced fore and aft along the said container, one stop for each of said divider plates each of which is offset from the next adjacent stop for selectively engaging the divider plates on the backward movement of the ejecting means whereby the driving connection between the plates and the ejecting means is broken and the divider plates spaced in their original ice block forming positions within the container.

6. A device for forming and dispensing ice blocks comprising a container having an outlet and adapted to receive a liquid to be frozen, a plurality of divider plates positioned one behind the other in longitudinally spaced relation along the container and cooperating with the walls of the container to form ice cube compartments, a

pair of edges on each of said divider plates, the said pair of edges on each divider plate from the front divider plate to the divider plate next to the rearmost divider plate being positioned farther apart than the corresponding edges on the adjacent divider plate in the rear thereof, ejecting means longitudinally movable forwardly and backwardly of said container, said ejecting means on its forward movement being adapted to loosen the ice blocks and move the ice blocks and said divider plates through said outlet to dispense the ice blocks, a plurality of pair of stops positioned in longitudinally spaced relation along the said container, the stops of each pair being spaced farther apart than the stops of the adjacent pair in the rear thereof, and means cooperating with said ejecting means on its backward movement for returning the divider plates into the container whereby each pair of edges on each divider plate cooperates with its corresponding pair of stops on the container to position each of the divider plates in their original ice block forming positions within the container.

7. A device for forming and dispensing ice blocks comprising a container having an outlet and adapted to receive a liquid to be frozen, a plurality of divider plates cooperating with the walls of the container to form ice cube compartments, an ejector plate positioned in the container in the rear of said divider plates, a push and pull shaft connected to said ejector plate and extending lengthwise of the container whereby when the said shaft is pulled forwardly the ejector plate loosens the ice blocks and moves the ice blocks and said divider plates through said outlet to dispense the ice blocks, a breakable connection between each of the divider plates and said push and pull shaft, a plurality of stops positioned lengthwise of the said container in spaced relation, an edge on each of said divider plates for cooperating with its respective stop on the said container whereby on the push or backward movement of the said shaft the cooperating edges on the divider plates and the stops on the container selectively position the divider plates in their original ice block forming positions within the container and the breakable connection permits the said shaft to move relatively to the divider plates while held by their respective stops.

8. A device for forming and dispensing ice blocks comprising a container having an outlet and adapted to receive a liquid to be frozen, a plurality of divider plates cooperating with the walls of the container to form ice cube compartments, an ejector plate positioned in the container in the rear of said divider plates, a push and pull shaft connected to said ejector plate and extending lengthwise of the container whereby when the push and pull shaft is pulled forwardly the ejector plate loosens the ice blocks and moves the ice blocks and said divider plates through said outlet to dispense the ice blocks, a breakable connection between each of the divider plates and said push and pull shaft, a closure for the outlet end of the said container also having a breakable connection with the said push and pull shaft, a plurality of stops positioned lengthwise of the said container in spaced relation, a stop on each of said divider plates for cooperating with its respective stop on the said container whereby on the push or backward movement of the push and pull shaft the cooperating stops on the divider plates and container selectively position the divider

plates in their original ice block forming positions within the container and the breakable connection permits the push and pull shaft to move relatively to the divider plates while held by their respective stops.

9. A device for forming and dispensing ice blocks comprising a container having an outlet and adapted to receive a liquid to be frozen, a plurality of divider plates cooperating with the walls of the container to form ice cube compartments, an ejector plate positioned in the container in the rear of said divider plates, a fixed guide rod extending longitudinally of said container, a push and pull shaft slidably mounted on said guide rod and connected to said ejector plate, whereby when the said shaft is pulled forwardly the ejector plate loosens the ice blocks and moves the ice blocks and said divider plates through said outlet to dispense the ice blocks, a breakable connection between each of the divider plates and said push and pull shaft, a plurality of stops positioned lengthwise of the said container in spaced relation, and edge on each of said divider plates for cooperating with its respective stop on the said container, whereby on the push or backward movement of the said shaft the cooperating edges on the divider plates and the stops on the container selectively position the divider plates in their original ice block forming positions within the container and the breakable connection permits the said shaft to move relatively to the divider plates while held by their respective stops.

10. A device for forming and dispensing ice blocks comprising a container having an outlet and adapted to receive a liquid to be frozen,

one or more divider plates cooperating with the walls of the container to form ice cube compartments, an ejector plate positioned at the rear of said divider plates, a shaft connected to the ejector plate and extending lengthwise of the said container, a handle, cooperating screw means on said handle and said shaft adapted for rotation to pull the shaft and ejector plate forwardly to loosen the ice blocks and ejector plate from the said container whereby the shaft and ejector plate can be pulled forwardly to move the ice blocks and said one or more divider plates through the outlet to dispense the ice blocks.

11. A device for forming and dispensing ice blocks comprising a container having an outlet and adapted to receive a liquid to be frozen, one or more divider plates cooperating with the walls of the container to form ice cube compartments, an ejector plate positioned at the rear of said divider plates, a shaft connected to the ejector plate and extending lengthwise of the said container, a handle, a cooperating nut and screw one of which is fixed to the handle and the other of which is fixed to the shaft, a rotary bolt connected to said handle, cooperating keeper means on the said container whereby when the handle is rotated to disengage the bolt from the keeper the cooperating nut and screw move the shaft and ejector plate forwardly to loosen the ice blocks and ejector plate from the container and the handle thereafter can be pulled forwardly to move the ice blocks and said one or more divider plates through the outlet to dispense the ice blocks.

RICHARD A. BAYNE.
